UNITED STATES PATENT OFFICE.

CARLTON L. KENNEDY, OF SOUTH BRAINTREE, MASSACHUSETTS, ASSIGNOR TO THE HOLTZER-CABOT ELECTRIC COMPANY, OF BROOKLINE, MASSACHUSETTS, A CORPORATION OF MASSACHUSETTS.

ENGINE-STARTER.

1,189,260.

Specification of Letters Patent.

Patented July 4, 1916.

Application filed September 25, 1912. Serial No. 722,201.

To all whom it may concern:

Be it known that I, CARLTON L. KENNEDY, a citizen of the United States, residing at South Braintree, in the county of Norfolk 5 and State of Massachusetts, have invented certain new and useful Improvements in Engine-Starters; and I do hereby declare the following to be a full, clear, and exact description of the invention, such as will 10 enable others skilled in the art to which it appertains to make and use the same.

The present invention relates to engine starters, and more particularly to starters for internal combustion engines, such as automobile engines, in which a dynamo-electric machine is used as a dynamo to charge 15 a storage battery and as a motor to start the engine.

The object of the invention is to produce 20 a simple and efficient system of this type in which the dynamo-electric machine is self-regulated when running as a dynamo, and is arranged to give a large torque when it operates as a motor to start the engine. 25 With this object in view, the present invention consists in the engine starter herein-after described and particularly pointed out in the claims.

In the accompanying drawings, illustrating 30 the preferred form of the invention, Figure 1 is a diagram of the system; and Fig. 2 a detail of construction.

The automobile engine E, the gearing G and the pump P are all as is common in automobiles, the pump shaft being directly 35 geared with the crank shaft of the engine. Connected with the pump shaft is a dynamo-electric machine which is thereby directly connected with the engine and adapted to 40 drive it for starting, or to be driven by it for generating current for the purpose of supplying the various current consuming devices on the machine, such as head lights H' and H², the side lamps L' and L², the dash lamp L³, tail lamp L⁴ and horn or other 45 warning signal W, and also the ignition system I. The starting switch S is employed for making the necessary connections to operate the dynamo-electric machine D as a motor. The horn button w is provided 50 in the horn circuit for use in operating the horn W.

In the illustrated embodiment of the invention, the dynamo-electric machine B has both shunt and series field windings. The 55 shunt winding is indicated at C'. The series winding is divided into two sections or coils indicated at C² and C³, the section or coil C² being of lower resistance than the section or coil C³. The dynamo-electric machine 60 commutator is indicated at A and the cut-out is indicated at O. The cut-out O is illustrated in detail in Fig. 2. The cut-out is a centrifugal switch and operates to close the circuit upon which it is located upon the attainment by the dynamo-electric machine of 65 a predetermined critical speed. The particular cut-out shown forms no part of the present invention, but is one which has been found to give satisfaction in work of this 70 kind. Three 120 degree collector ring segments 1, 2 and 3 insulated from each other and from the dynamo-electric machine shaft are supported on the shaft 4, being keyed thereto. Brushes 14 and 140 bear upon the 75 collector ring at diametrically opposite points, and consequently the insulation between the segments insulates the brushes from each other. The centrifugal switch member consists of two segmental heads 5 80 and 6 secured to the ends of a spring 7, in turn secured to the hub 8. The spring 7 holds the switch heads 5 and 6 contracted in the position shown in Fig. 2 until the critical speed is reached, at which time the 85 heads 5 and 6 fly outwardly and make contact with the inside of the collector ring formed by the three segments 1, 2 and 3. The heads 5 and 6 are electrically connected by means of the spring 7 and when they fly 90 outwardly, they electrically connect the two segments 1 and 3. The spring 7 is electrically connected with the segment 2 by means of the contact spring 9 which bears against the inside of the segment 2 so that when 95 the critical speed is reached, the collector ring becomes a continuous conductor, and the cut-out O completes the circuit in which it is located.

The connections between the parts of the 100 apparatus will be described in connection with a description of the operation of the system in performing the various functions which it discharges. Beginning with the

automobile in a state of rest and the engine not running. Assuming that the storage battery is properly charged, the operator deciding to start the engine, closes the starting switch S. At this time the cut-out is open and the current from the end pole 10 of the battery runs through the wire 11 to the series field coil C², thence through the wire 12 to the starting switch S, thence 5 through the wire 13 to the cut-out brush 14, thence through the wire 15 to the commutator brush connection 16, through the armature A to the commutator brush connection 17, thence through the wire 18 to the end pole 190 of the battery. The series 10 field coil C² is made of few turns of heavy wire. This is a circuit of low resistance which allows a very heavy current to flow through the dynamo-electric machine which 15 acts as a compound wound motor and exerts a very heavy torque which is sufficient to start the engine even under unfavorable 20 conditions.

While in the illustrated embodiment of 25 the invention, the series field windings are shown as arranged in two sections C² and C³, and so connected that the current flows through both sections in series when the dynamo-electric machine is driven as a 30 dynamo in order to secure an efficient regulation of the dynamo, and through the section C² only when the dynamo-electric machine is being run as a motor in order that a series field circuit of low resistance may 35 be provided to permit a large current to pass through the armature when the machine is run as a motor, it is obvious that other arrangements of the series field winding might be had to produce these results, 40 and the invention is, therefore, not limited to the particular arrangement of series field winding and its connections shown in the drawings, but the series field winding may be otherwise arranged and connected within 45 the scope of the claims.

The speed at which the dynamo-electric machine D runs as a motor is lower than the critical speed at which the heads 5 and 6 engage the collector ring of the cut-out O. 50 Consequently, the cut-out O operates to cut out the other series field coil C³ when the dynamo electric machine D runs as a motor. The storage battery is a 12 volt battery and the entire current from the battery is available 55 for use in driving the motor. The starting switch should open as soon as the engine starts, and it acts to open as soon as pressure upon it is removed. As soon as the engine starts and increases in speed sufficiently to 60 bring the dynamo-electric machine armature up to the critical speed, the cut-out O operates to close the circuit which it has held open, and with the opening of the starting switch and the closing of the cut-out O, the dynamo-electric machine becomes a dy-

namo and operates to generate current for charging the storage battery.

The conditions for charging the storage battery are that the engine should be running at a speed sufficiently high to cause the cut-out O to close the circuit in which it is located, and thereupon the dynamo-electric machine D, acting as a dynamo, operates to charge the storage battery B. The current generated by the dynamo-electric machine is taken off at one commutator brush connection 16 and flows through the wire 15 to the cut-out brush 14, thence through the cut-out O, the cut-out brush 140, the wire 19, through the series field coil C³ and the series 75 field coil C², and thence through the wire 11 to the pole 10 of the storage battery. The other armature brush 17 is connected by the wire 18 with the other pole 190 of the storage battery. The series field coil C³ is made 80 of a much larger number of turns of smaller wire than the series field coil C². These coils are composed of enough windings or turns of wire so that the current can never reach a value which will damage the storage battery B.

The operation of the system for use in supplying current to the various current consuming devices of the machine, to wit, the head, side, tail and dash lights and the 90 horn and the ignition system, is such that they are fed directly from the armature through the cut-out without passing through the series field coils. As a consequence of which, the current consumed for these 95 devices has no material effect upon the charging current for the battery which is approximately constant irrespective of the amount of current used for such devices. The circuits for the various current consuming devices when the dynamo-electric machine is a dynamo are as follows. Starting with the commutator brush connection 16, the connection is through the wire 15 to the cut-out O, to wire 20 which is a lead wire to 100 one side of four of the current using devices. The connection is as follows:—through the wire 21, to the controlling switch 22, through the wire 23 to the right hand head light H², thence through the wire 115 24 to the neutral wire 25; through the wire 26, switch 27, wire 28 to the side lamp L², thence through the wire 29 to the neutral wire 25; through the wire 30, the switch 31, the wire 32 to the tail lamp L⁴, and thence 120 through the wire 33 to the neutral wire 25; and through the wire 34 and button w (when it is closed) and the wire 35 to the horn W which connects by the wire 36 with the neutral connection 25 of the right hand side 125 lamp L². From the other pole 17 of the armature connection is had through the wire 18 to the lead wire 37 and from this lead wire or generator main connection is had through the wire 38, the switch 39, the wire 130

40 to the left hand head light H' , and thence through the wire 41 to the neutral wire 25; through the wire 42, the switch 43, the wire 44 to the left hand side lamp L' , thence 5 through the wire 45 to the neutral wire 25; through the wire 46, switch 47, the wire 48 to the dash lamp L^3 , and thence through the wire 49 to the neutral wire 25; and through the wire 50, switch 51, wire 52 to the ignition system I, and thence through the wire 10 53 to the neutral wire 25. In cases where the engine is running at low speed and a considerable amount of current is taken by the current consuming devices, the voltage drop 15 due to the passage of this current through the armature may be enough to cause its voltage to drop below that of the storage battery, and this brings us to a consideration of the case where the current consuming devices 20 are fed by the battery and the dynamo-electric machine, operating as a dynamo, in coöperation with each other. For here part of the current will flow from the battery through the series coils, thus increasing the 25 field magnetism of the dynamo and thereby increasing the voltage to a point where it will approximately equal that of the battery.

In case the current consuming devices 30 (and in this case the ignition system is to be excluded) demand current when the engine is not running, the current will be drawn from the storage battery, partially from one end and partially from the other 35 end thereof, the neutral wire 25 being connected to the middle terminal 250 of the storage battery, as shown, one half of the current operating devices drawing their current from one end of the storage battery, 40 and the other half drawing from the other end of the storage battery. Under these circumstances, that is, when the current consuming devices demand current and the engine is not running, the cut-out is open and 45 the wires 15 and 18 are dead. Then the feeder 20 will draw its current through the wire 19, the series field coils C^3 and C^2 , and the wire 11 from pole 10 of the battery and the devices drawing current from this feeder 50 20 will be connected with the neutral wire, and therefore with the middle terminal 250 of the storage battery. The feed wire 37 will draw its current from the opposite pole 190 of the storage battery, and the devices 55 supplied with current by this feeder will, as above described, be connected through the neutral wire with the middle terminal of the battery. The left hand head light H' , the left hand side lamp L' , the ignition I 60 and the dash lamp L^3 are supplied with current by that half of the storage battery between the middle terminal 250 and the end pole 190, while the right hand head light H^2 , the right hand side lamp L^2 , the 65 horn W and the tail lamp L^4 draw their

current from that portion of the storage battery between the pole 10 and the middle terminal 250, four current consuming devices being connected with each half of the battery.

From motives of economy it is desirable to use the comparatively cheap lead plate storage battery. This form of battery is injured if it receives an excessive current or is over-charged with any considerable volume of current. The system of the present invention is so arranged that at no time will the battery B be charged with any considerable volume of current. If the conditions are such that there is a tendency for any considerable volume of current to flow into the battery B, this current will, by passing through the series coils C^2 and C^3 , weaken the dynamo field and this automatically decreases the dynamo voltage, and consequently limits the current furnished to the battery. This effect is accentuated by the use of the high resistance field coil C^3 which has a large number of windings. The large number of current turns in the fine windings of the coil C^3 has such a weakening effect upon the dynamo field that under no conditions is it possible to cause a current to flow through the series field C^3 of a volume sufficient to damage the battery. Moreover, the resistance of the series field C^3 acts as a ballast resistance to prevent too great a charging current from flowing into the battery. The system thus automatically prevents the battery from being damaged by an excessive charging current, and the cheaper lead storage battery may be used instead of the more expensive nickel-iron storage battery which is not injured by such over-charging.

The illustrated embodiment of the present invention is intended for use in connection with automobile engines, but is equally adapted for use with motor-boat and other engines, and the claims are to be read and understood as comprehending such uses of the invention. The invention is not limited to the illustrated embodiment as it may be embodied in other forms within the scope of the following claims.

I claim—

1. The combination of an engine, a storage battery, a current consuming device, a direct current dynamo-electric machine connected with the engine to draw current from the storage battery as a motor to start the engine and to be driven by the engine as a dynamo to furnish current to the current consuming device and for charging the storage battery, said dynamo-electric machine having an armature, a shunt field winding connected across the armature and a series field winding, a circuit from the armature through the current consuming device, a circuit from the armature through the se- 130

ries field winding and the battery, said series field winding being so wound that when the battery receives current the machine field is weakened and when the battery furnishes current the field is strengthened by the current in the circuit through the armature, series field winding and battery, a cut-out open when the machine is at rest and closed when the machine is running at full speed, and a connection containing a starting switch shunting the cut-out.

2. The combination of an engine, a storage battery, a current consuming device, a direct current dynamo-electric machine connected with the engine to draw current from the storage battery as a motor to start the engine and to be driven by the engine as a dynamo to furnish current to the current consuming device and for charging the storage battery, said dynamo-electric machine having an armature, a shunt field winding connected across the armature and a series field winding, a circuit from the armature through the current consuming device, a circuit from the armature through the series field winding and the battery, an automatic cut-out in the circuit through the armature and battery closed when the dynamo-electric machine is running as a dynamo and open when the dynamo-electric machine is running as a motor, and a connection shunting the cut-out and containing a starting switch to lead current around the cut-out to operate the dynamo-electric machine as a motor to start the engine.

3. The combination of an engine, a storage battery, a current consuming device, a direct current dynamo-electric machine connected with the engine to draw current from the storage battery as a motor to start the engine and to be driven by the engine as a dynamo to furnish current to the current consuming device and for charging the storage battery, said dynamo-electric machine having an armature, a shunt field winding and a series field winding divided into two sections one of which is of higher resistance than the other, an automatic cut-out closed when the machine is running as a dynamo and open when running as a motor, a connection through the armature and cut-out to the current consuming device, a connection through the armature, cut-out and both sections of the series field winding to the battery, said series field winding being wound so that the field is strengthened when current flows from the battery and weakened when current flows to the battery, and a shunt connection containing a starting

switch around the cut-out and the higher resistance section of the series field winding.

4. The combination of an engine, a storage battery, a current consuming device, a direct current dynamo-electric machine connected with the engine to draw current from the battery as a motor to start the engine and to be driven by the engine as a dynamo when the engine is running to furnish current to the current consuming device and for charging the storage battery, said dynamo-electric machine having an armature, a shunt field winding and a series field winding divided into two sections, one of which is of higher resistance than the other, a connection from the armature to the current consuming device, a connection from the armature through both sections of the series field winding to the battery, said series field winding being wound so that when the current flows to the battery the field is weakened and when the current flows from the battery the field is strengthened, a cut-out in the connection between the armature and the battery, and a connection containing a starting switch shunting the cut-out and a higher resistance section of the series field winding.

5. The combination of an engine, a storage battery, a direct-current dynamo-electric machine connected with the engine to draw current from the storage battery as a motor to start the engine and to be driven by the engine as a dynamo to furnish current for charging the storage battery, said dynamo-electric machine having an armature, a shunt field winding and a series field winding divided into two sections, one section being of higher resistance than the other, connections including a cut-out closed when the machine is running as a dynamo and open when the machine is at rest for leading the current through the higher resistance section of the series field winding to charge the battery, and connections including a starting switch for leading the current around the cut-out and through the lower resistance section of the series field winding for driving the machine as a motor, the series field winding being so wound as to oppose the shunt field winding when the machine is charging the battery and aid the shunt field winding when the machine is run as a motor.
